ATTORNEY

UNITED STATES PATENT OFFICE

JACOB G. LEIBOLD, OF SAN FRANCISCO, CALIFORNIA

COLLAPSIBLE CREEL

Application filed June 11, 1930. Serial No. 460,368.

The present invention relates to improvements in collapsible creels and more particularly to those constituted of a plurality of pockets convertible into compartments adaptable to the carriage of diverse devices employed by persons following fishing as a diversion.

The primary object of the present invention is to provide a collapsible creel constituted of a plurality of pockets, or separate and distinct receptacles, adapted for the reception and carriage of not alone fish, but also of such segregated articles and devices as are ordinarily carried by fishermen and used by them in the prosecution of their piscatorial pleasures.

An additional object is to provide a multi-pocketed collapsible creel constituted of non-permeable to water material arranged for the convenience of fly casters and such like fishermen for pleasure.

The creel comprises a main pocket, or compartment, adapted to be collapsed when not in use, and carrying interiorly, by means of 25 snaps, a second pocket of rubberized or rubber-lined material adapted to be removably attached interiorly thereto, there being also provided for and carried by this pocket a spreader adapted to be positioned in such 30 manner, when desired, as to hold open said pocket and its interiorly borne rubber-lined pocket, and at other times to occupy a prone position permitting the collapse of these two elements. The main flap is an extension of 35 the back section of the main pocket and is provided with an opening covered by a smaller flap, snap-secured in covering position, the lifting of which permits the introduction of fish into the rubber-lined pocket. The 40 main flap is further provided with fastening means for securing this flap in closed relation with both the main and auxiliary pockets. Frontally of the main pocket there is secured an auxiliary collapsible pocket adapted to be 45 used for the carriage of miscellaneous articles, this pocket being provided, also, with an individual flap for its closure. Attached to the front of this auxiliary pocket, or compartment, are three other pockets, the central 50 of which is provided interiorly, front

and rear surfaces, with a lining of sheep-skin adapted for the carriage of artificial flies, the two surfaces being separated by a leaf for the prevention of entanglement of flies carried respectively by the opposed surfaces. 55 The front of this fly-pocket is secured along its vertical edges by zippers, and along its lower edge by stitching securing it centrally to the front edge of the creel, the upper edge being left in free, or open, relation with the front of the auxiliary compartment. Flanking this fly-pocket, and secured at the sides and bottoms to the auxiliary pocket by means of rows of stitching, are two pockets with open upper mouths adapted to serve as extra receptacles for hooks, lines, and other such paraphernalia. The front of these two pockets is provided with buckles for the accommodation of straps carried by the auxiliary pocket's flap and adapted to hold these elements in closed relation, a buckle being carried centrally by the bottom of the creel for the accommodation of a fastening strap carried by the main flap. Additionally, there are provided rings carried by the opposite upper edges of the continuous union strip uniting the front and rear sections of the main pocket, this strip being adapted for collapsing bellow-wise, when the creel is not in use, and carries in its sides ventilating openings. 60 The front section of the auxiliary pocket is united to the front section of the main pocket, which constitutes, also, the rear section of the auxiliary pocket, by means of a like strip adapted likewise for collapsing bellow- 65 wise when not in use, both these strips being secured to the edges of their respective sections by means of rows of stitching. There is further provided a neck-strap whose ends carry snap-hooks adaptable for being 70 snapped onto the rings previously mentioned for support of the creel about the neck of the angler, as well as a strap serving as a 75 part-girdle for its waist support. 80

In the accompanying one sheet of drawings, forming a part of this specification, and, in which, similar characters of reference designate like parts, throughout:

Figure 1 is a perspective view of the preferred form of creel, showing the main and 100

auxiliar pockets with their flaps lifted to expose their interior arrangements, the uniting bellow-like collapsing strips for the sides and bottoms of each, the arrangement of the 5 frontally borne pockets, the flap-securing means, the zipper means borne by the fly-pocket, and the means for securing the creel to the body of the angler;

Figure 2 is a modification of the creel 10 shown in Figure 1, but of simpler construction, certain compartments having been eliminated to provide a lighter and cheaper creel;

Figure 3 is a mutilated perspective view, an end having been removed to permit of a 15 view of the spreader in position for retaining the main pocket and its contained rubber fish-containing pocket in open position; and

Figure 4 is a perspective view of the rectangular wire spreader, operating to keep the 20 mouths of the main pocket and its detachable and interiorly arranged fish receptacle in open mouthed relation to each other, and showing, additionally, the fabric strip 38 whereby the one side of this spreader is hing- 25 edly secured, by rows of stitching, with the upper inner surface of the rear section of the main pocket 5.

Referring more particularly to the drawings, the numeral 4 indicates a perspective 30 view of the preferred form of the invention, wherein 6 represents the rear section of the main pocket 5, together with its extension 7, representing the main flap over-all having therein a fish-slot 8 provided with a covering-flap 9. The main pocket 5 is constituted of the rear section 6 and a front section 6', these two sections being united by a continuous strip 29 creased for folding bellow-like, as indicated at 29', with its end sections bearing 35 ventilating eyelets 30, the respective edges of this strip being secured to the rear and front sections by means of rows of stitching, this strip constituting the ends and bottom of said main pocket. An adjustable wire separator, or spreader, 13, of rectangular form 40 and of a size to fit the mouth of this pocket, when extended, is provided and is held in retained relation with the rear upper edge of this pocket by means of a strip of fabric 38 45 stitched to the front surface of the rear section 6 near its top by spaced rows of stitching, not shown, affording therebetween space for the accommodation and support of one of the sides of the rectangularly shaped spreader 50 13. Interiorly of the main pocket 5 there is fitted a detachable rubber-lined pocket 13' bearing about its upper edges snaps 15 adapted, when snapped-in, to hold the detachable pocket 13' in retained relation with the interior of the main pocket 5, this arrangement 55 permitting the detachment and removal of the rubber-lined pocket 13' for the purpose of cleansing, when required. When it is desired 60 to retain the main pocket 5 and its detachable rubber-lined pocket 13' in extended

relation, it is only necessary to unsnap the frontal fastening members 15 and raise the free side of the rectangular frame 13 to a horizontal position just above the snaps 15 and resnap these fasteners, bringing the two edges 70 of the pockets 5 and 13' again into normal relation. When it is desired to collapse this pocket, it is only necessary to unfasten these two edges, drop the rectangular spreader into

prone position and again fasten the free edges 75 of the two pockets by means of these snaps. An auxiliar pocket, or compartment, 16 is attached to the front of the main pocket 5 and provides an additional receptacle for miscellaneous articles and is secured to the frontal 80 section of the main pocket 5 by a uniting strip 28 of less width than that of the strip 29, but likewise of collapsible character. To the outer surface of the front of the pocket 16, there is secured centrally a third minor pocket 85 comprising a snelled hook space 17, a sheep-skin lined space 21—22 for flies separated by a leaf 23 the sides of this minor pocket being secured in place by means of zippers 24, the bottom being secured to the bottom of the auxiliar pocket by rows of stitching. Extra 90 minor pockets 20 and 20', of collapsible character, as indicated at 27 and 27', are provided as additional receptacles to add to the angler's 95 convenience. The fronts of these pockets are provided with buckles 37 for the accommodation 100 of straps 12 and 12' stitched, or riveted, to the frontal walls of these pockets and serve as means for securing in place over the mouth of the auxiliar pocket 16 and the mouths of the minor pockets 20 and 20', the auxiliar flap 14, these being additionally covered and secured in place by the strap 11 carried by the main flap 7, which acts as a coverall for these pockets and the main pocket 5, as well, this strap being received and held by the buckle 26.

For the support and carriage of the creel by the angler, there is provided a shoulder strap 10 and a back, or girdling, strap 31, these being provided at their extremities with snap-hooks 35 adapted for engagement with rings 34 secured to opposite sides of the creel near its top edge by means of straps 33 riveted or otherwise secured thereto, these 115 straps being further provided with adjusting buckles 36 and 32.

The creel is constructed of waterproof yarn-dyed canvas, and combines a plurality of necessary units so arranged as to add immeasurably to the efficiency, convenience and comfort of the angler. For the catch, a detachable rubber-lined receptacle is provided that is readily detachable and removable for cleansing.

For additional supplies, extra compartments are provided affording ample room for leaders, lines and special equipment. The device as constructed, conveniently replaces the ordinary bulky creel and the many 120 125 130

bulky pockets carried by the usual angler's coat. The zipper pockets for flies have two sides lined with sheep-skin, between which there is inserted a fabric leaf insuring against injury and supplying space for complete sets of flies safely and conveniently arranged and carried, there being also provided a special rear space for snelled hooks. Ventilating side holes are also provided, affording a plentiful supply of pure air to keep the catch fresh. The device is easily and comfortably worn, fits snugly against the side and is secured in place by straps over the shoulder and about the waist. When in use it stands rigid, and when not in use it is readily collapsible and lies flat against the body.

Having thus described my invention, I claim, and desire to secure by Letters Patent of the United States the following:

1. In an angler's creel, a collapsible member comprising a main pocket having as an integral part thereof a flap-covering therefor provided with a fish-slot, and a flap cover for said fish slot.

2. In an angler's creel, a collapsible member comprising a main pocket having a flap-covering therefor provided with a fish-slot covered by a flap, a detachable rubber-lined fish-pocket, and snap-fastening means borne interiorly by the upper edges of said main pocket and the upper edges of said fish-pocket for holding the latter in suspended relation with the former.

3. In an angler's creel, a collapsible pocket comprising a back section provided with an extension therefrom forming a flap with a fish-slot therein and a flap-covering therefor, a front section having an extension forming a flap therefor, and a bellow-strip bearing ventilating openings in its near extremities, said strip being so united by stitching to said rear and front sections as to serve as collapsible ends and bottom of said main pocket.

4. In an angler's creel, a collapsible main pocket comprising a back section provided with an extension therefrom forming a flap having a fish-slot therein and covering means therefor, a front section bearing an extension forming a flap, a bellow-strip bearing ventilating openings, said strip being secured to the edges of said rear and front sections to form collapsible ends and bottom for said main pocket, and a rectangular-shaped wire-spreader having a longer side hingedly secured to a surface of the near upper edge of said rear section of said main pocket, said wire spreader being adapted, when raised and lowered, to open and close the mouths of said main and said fish-pockets.

5. The combination, with a collapsible main pocket constituted of a flexible fabric and bearing as an integral part thereof a main flap having a flap-covered fish-slot, of

an auxiliar pocket formed frontally of the main pocket by uniting the side and bottom edges of said main pocket to a continuous bellow-strip of like material to constitute the collapsible sides and bottom of said auxiliar pocket and similarly uniting the corresponding opposite edges of said bellow-strip to a front section of flexible material bearing an extension fashioned to serve as a flap-covering for said pocket, and means for securing said covering in place.

6. The combination with a collapsible main pocket bearing as an integral part thereof a main flap having a flap-covered fish-slot, of an auxiliar pocket formed frontally of said main pocket by uniting the side and bottom edges of said main pocket to a continuous bellow-strip to constitute the collapsible sides and bottom of said auxiliar pocket and similarly uniting the corresponding opposite

edges of said bellow-strip to a front section of flexible material bearing an extension fashioned to serve as a flap-covering for said pocket, means for securing said covering in place, a special pocket frontally borne by

said auxiliar pocket and divided into a rear compartment for carrying snelled hooks, and a second sheep-skin lined compartment adjacent thereto and divided by a leaf-like partitioning means for its separation into separate fly-bearing sections, said last named pocket being secured at its bottom to the frontal edge of said auxiliar pocket by rows of stitching and at its side edges by zipper fastenings, the upper edges being open and constituting mouths therefor.

7. The combination with a collapsible main pocket bearing as an integral part thereof a main flap having a flap-covered fish-slot of an auxiliar pocket formed frontally of the main pocket by uniting the side and bottom edges of said main pocket to a continuous bellow-strip to constitute the collapsible sides and bottom of said auxiliar pocket and similarly uniting the corresponding opposite

edges of said bellow-strip to a front section of flexible material bearing an extension fashioned to serve as a flap-covering for said pocket, means for securing said covering in place, a special pocket frontally borne by said auxiliar pocket and divided into a rear compartment for carrying snelled hooks, a second sheep-skin lined compartment adjacent thereto and divided by a leaf-like partitioning means for its separation into separate fly-bearing sections, said last named pocket being secured at its bottom to the frontal edge of said auxiliar pocket by rows of stitching and at its side edges by zipper fastenings, the upper edges being open and constituting mouths therefor.

8. The combination with a collapsible main pocket bearing as an integral part thereof a main flap having a flap-covered fish-slot of an auxiliar pocket formed frontally of the main pocket by uniting the side and bottom edges of said main pocket to a continuous bellow-strip to constitute the collapsible sides and bottom of said auxiliar pocket and similarly uniting the corresponding opposite

edges of said bellow-strip to a front section of flexible material bearing an extension fashioned to serve as a flap-covering for said pocket, means for securing said covering in place, a special pocket frontally borne by said auxiliar pocket and divided into a rear compartment for carrying snelled hooks, a second sheep-skin lined compartment adjacent thereto and divided by a leaf-like partitioning means for its separation into separate fly-bearing sections, said last named pocket being secured at its bottom to the frontal edge of said auxiliar pocket by rows of stitching and at its side edges by zipper fastenings, the upper edges being open and constituting mouths therefor, pockets flanking said special

sub-divided pocket and attached by bellow-strips to the front surface of said auxiliar pocket and adapted to be covered, initially, by the flap of said auxiliar pocket and addi-

tionally by the said main flap, and means for securing both main and auxiliar flaps in closed relation with each other and with all of said pockets.

- 5 8. The combination with a collapsible main pocket bearing as an integral part thereof a main flap having a flap-covered fish-slot, of an auxiliar pocket formed frontally of the main pocket by uniting the side and bottom edges of said main pocket to a continuous bellow-strip to constitute the collapsible sides and bottom of said auxiliar pocket and similarly uniting the corresponding opposite edges of said bellow-strip to a front section 10 of flexible material bearing an extension fashioned to serve as a flap-covering for said pocket, means for securing said covering in place, a special pocket frontally borne by said auxiliar pocket and divided into a rear compartment for carrying snelled hooks, a second sheep-skin lined compartment adjacent thereto and divided by a leaf-like partitioning means for its separation into separate fly-bearing sections, said last named pocket being secured at its bottom to the frontal edge 15 of said auxiliar pocket by rows of stitching and at its side edges by zipper fastenings, the upper edges being open and constituting mouths therefor, pockets flanking said special sub-divided pocket and attached by bellow-strips to the front surface of said auxiliar pocket and adapted to be covered, initially, by the flap of said auxiliar pocket and additionally by the said main flap, means 20 for securing both main and auxiliar flaps in closed relation with each other and with all of said pockets, and adjustable means for securing said creel about the body of an angler.
- 40 9. The combination, in an angler's creel, of a main pocket having suspended interiorly a detachable waterproof fish-pocket with means for extending the mouths of said main and said fish pocket in open position, 45 an attached auxiliar pocket, said main and attached pockets being each provided with flaps for covering their respective open mouths, the main flap being additionally provided with a flap-covered fish-slot, minor 50 pockets carried frontally by said auxiliar pocket, the central of said minor pockets being divided into compartments for carrying supplies of flies and snelled hooks, the sides of said central pocket being secured by zippers permitting its front to be hingedly 55 dropped to expose its interior, and means for supporting said creel about the body of an angler, said means comprising adjustable shoulder and waist straps bearing upon their 60 respective extremities snap-catches adapted for engagement with rings permanently secured to opposite sides of said main pocket near its upper opposite edges.

10. In an angler's creel of the character 65 described, a main pocket and an auxiliar

pocket having therebetween a partitioning means, each of said pockets being provided with a bottom and sides adapted to be collapsed bellow-wise, the sides of said main pocket being provided with ventilating eyelets, and bearing detachably secured therewithin a waterproof receptacle for receiving a fish-catch. 70

11. In an angler's creel of the character described, a compartment, constituting a main pocket, comprising a back and a front section having as a bottom and sides a uniting strip adaptable to be collapsed bellow-wise and bearing in those sections constituting its ends ventilating eyelets, a flap borne 75 by said rear section provided with a flap-covered fish-slot with means for securing the flap borne by said rear section in closed relation relative to said compartment, and means for supporting said compartment upon the 80 person of an angler.

12. In an angler's creel of the character described, a compartment, constituting a main pocket, comprising a back and a front section having as a bottom and sides a uniting strip adapted to be collapsed bellow-wise and bearing in those sections constituting its ends ventilating openings, a flap borne by 90 said rear section provided with a flap-covered fish-slot with means for securing the flap borne by said rear section in closed relation relative to said compartment, means for supporting said compartment upon the person 95 of an angler, a catch retaining waterproof receptacle detachably borne by said compartment, and mouth distending means for both said compartment and said waterproof receptacle. 100

In testimony whereof I hereunto affix my 105 signature.

JACOB G. LEIBOLD.
